H. A. SCHMIDT,
FASTENING DEVICE,
APPLICATION FILED DEC. 7, 1921.

1,416,756.

Patented May 23, 1922.

Inventor

Henry A. Schmidt

UNITED STATES PATENT OFFICE.

HENRY A. SCHMIDT, OF PHOEBUS, VIRGINIA.

FASTENING DEVICE.

1,416,756.

Specification of Letters Patent. Patented May 23, 1922.

Application filed December 7, 1921. Serial No. 520,608.

To all whom it may concern:

Be it known that I, HENRY A. SCHMIDT, a citizen of the United States, residing at Phoebus, in the county of Elizabeth City 5 and State of Virginia, have invented certain new and useful Improvements in Fastening Devices, of which the following is a specification.

This invention relates to fastening devices 10 especially adapted for use in securing floor coverings in position.

An important object is to provide a fastening device having novel means whereby the same may be employed for securing the 15 adjacent edges of a floor covering flatly in position so that the edges of the floor covering will not be permitted to curl or wear rapidly.

A further object is to provide a fastening device having novel means whereby the outer edges of a floor covering may be secured in position.

A further object is to provide a fastening device which is simple to apply, neat in 25 appearance and cheap to manufacture.

Other objects and advantages of the invention will be apparent during the course of the following description.

In the accompanying drawing forming 30 a part of this application and in which like numerals are employed to designate like parts throughout the same,

Figure 1 is a perspective of the fastening means for securing the outer edges of the 35 covering in position.

Figure 2 is a fragmentary perspective of a fastening device employed for connecting the meeting edges of the covering.

Figure 3 is a detail sectional view taken 40 on line 3—3 of Figure 1.

In the drawing wherein for the purpose of illustration is shown a preferred embodiment of the invention the numeral 5 designates a floor covering such as a piece of linoleum and which is adapted to be held in position by means of binding strips generally designated by the numeral 6. The binding strips are formed from lengths of metal each of which is bent longitudinally to provide 45 upper and lower covering contact strips or flanges 8 and 10 respectively. As illustrated in Figure 1, the end portion of one binding strip is extended into the adjacent end portion of another binding strip so as to provide 50 a neat connection and so as to provide an additional wearing surface at the corners 55

of the covering. Specifically, the upper and lower flanges 8 and 10 of one of the strips are received within the groove provided by the upper and lower flanges of the other 60 strip.

In the form of the invention illustrated in Figure 2 the fastening device is formed from a single length of metal 12 which is so formed to provide a means for connecting 65 the adjacent edges of the floor covering. The strip of metal 12 is formed intermediate its longitudinal edges with outwardly directed portions 14 drawn closely together so as to provide a metallic wall of a double thickness 70 between the meeting edges of the covering.

The metal between the outwardly directed portions 14 is flattened so as to provide a pair of oppositely directed flanges or walls 75 16 which lie flatly in contact with the top of the covering at the meeting edges of the same. It will be observed that the top flanges 16 and the base plates 18 formed by the bending process define oppositely arranged grooves which receive the edge portions of the floor covering.

As the upper flanges 16 are formed of upper and lower layers rounded outer edges are formed on the flanges 16 whereby rapid 85 wear on the fastening means is prevented.

Summarized, it might be stated that the construction illustrated in Figure 2 embodies a pair of base plates between which is located a T-shaped member having laterally 90 directed flanges which flatly contact with the top of the floor covering and being of a double thickness so as to prevent rapid wear.

In the use of the improved floor covering means, the covering is inserted into the 95 spaces between the flanges and the base plates and a sufficient space is left to allow for the expansion of the covering. Suitable fastening devices such as tacks may be employed for securing the metallic plates in 100 position.

I claim:

1. A fastening for floor coverings consisting of a pair of base plates, upwardly extending portions formed along the adjacent 105 edges of said base plates, and laterally directed flanges formed at the upper edges of said upwardly extending portions and cooperating with the base plates in defining a pair of grooves for the reception of the meeting edges of a floor covering.

2. A fastening for floor coverings consist-

ing of a pair of base plates, upwardly extending portions formed along the adjacent edges of said base plates, and laterally directed flanges formed at the upper edges of 5 said upwardly extending portions and co-operating with the base plates in defining a pair of grooves for the reception of the meeting of a floor covering, said laterally direct-

ed flanges consisting of upper and lower layers having their outer edges joined.

In testimony whereof, I have affixed my signature in the presence of two witnesses.

HENRY A. SCHMIDT.

Witnesses:

O. W. WARD,
EVANCE BUTLER.
